UNITED STATES PATENT OFFICE.

ARTHUR T. HAGEN, OF ROCHESTER, NEW YORK.

IRONING AND POLISHING MACHINE.

SPECIFICATION forming part of Letters Patent No. 366,092, dated July 5, 1887.

Application filed September 24, 1886. Serial No. 214,407. (No model.)

To all whom it may concern:

Be it known that I, ARTHUR T. HAGEN, of Rochester, in the county of Monroe and State of New York, have invented a new and useful 5 Improvement in Ironing and Polishing Machines, which improvement is fully set forth in the following specification and shown in the accompanying drawings.

Upon September 22, 1885, there was issued 10 to me a patent for an improved ironing-machine, No. 326,556, and my present invention is an improvement upon said machine.

In the machine patented the covered roller D is connected with the polishing-roller C in 15 such a manner that the former always rotates in the same direction—that is to say, in a direction contrary to that in which said polishing-roller rotates; and my improvement, hereinafter set forth, relates to providing means 20 by which said roller D may be turned in either direction, while the polishing-roller turns in only one direction, as before.

This improved machine is designed more particularly for ironing and polishing shirt-bo 25 soms, which, in the process of polishing, are passed backward and forward through between the rollers sidewise as many times as are necessary to produce the required polish, the reversing of the direction of motion of the 30 covered carrying-roller D being for the purpose of moving the shirt thus backward and forward. The friction of the polishing-roller C upon the fabric of the article being ironed is slight compared with the friction of the cov 35 ered roller D thereon, on account of which the latter roller controls the movements of the article being polished.

This improved machine is fully described hereinbelow, and more particularly pointed 40 out in the claims.

Referring to the accompanying drawings, Figure 1 is a side elevation of the improved ironing and polishing machine, (seen in the direction in which Fig. 2 in said Letters Patent is seen,) parts not essential to the figure being omitted; Fig. 2, a view drawn to a larger scale of the cam-wheel with connected parts, (seen in the direction indicated by arrow x in Fig. 1,) the frame being vertically sectioned, 45 as upon the dotted line x³, the figure being drawn to show in part the manner of stopping the motion of said wheel; Fig. 3, an end ele-

vation of the machine, parts being broken away, (seen as indicated by arrow y in Fig. 1,) drawn to further show the mechanism for reversing the motion of the covered roll; Fig. 4, a view, taken from the same direction, drawn to a larger scale, of the parts to effect the reversing of the motion of said roll, a part of the frame being shown in dotted lines, parts 50 shown in two positions by full and dotted lines; Fig. 5, a view of some of the upper parts of the machine, (seen in the opposite direction from that in which Fig. 3 is seen, or as indicated by arrow z in Fig. 1,) parts being broken 55 away to more clearly show other parts; Fig. 6, a plan of the upper parts of the machine, (seen as indicated by arrow x' in Fig. 1,) parts of the rolls being broken away; Fig. 7, a plan of the treadles and treadle-shaft, the 60 frame and treadle-rods being horizontally sectioned, as on the dotted line z' in Fig. 3; Fig. 8, an elevation of one side of the frame, with parts omitted, the frame being transversely vertically sectioned, as on the dotted line 75 x² in Fig. 1, the figure being drawn to a smaller scale, and seen as indicated by arrow x, to better show the relation between the treadle mechanism and the cam-wheel, the latter being shown in two positions by dotted 80 lines, other parts being shown in two positions by dotted and full lines; and Fig. 9, a plan of the cam-wheel and arm supporting it, with other combined parts, the frame being horizontally sectioned, as upon the dotted line y² 85 in Fig. 8, and viewed as indicated by the arrow pointed thereon.

Referring to the parts, A is the frame of the machine; b b', standards thereof; b³, a cross-tie for the standards; B, the main shaft, and d d' 90 bearings therefor; E, a second shaft; C and D, rollers; g and g', pulleys, and f and f' toothed wheels of the driving mechanism; r, the treadle-shaft, F the treadle, and i the treadle-rod of the treadle mechanism, and n the actuating-lever for the roll D, all corresponding to similar parts shown and described in the Letters Patent above mentioned.

I is a shaft I add to the machine for the purpose hereinafter fully stated, it being substantially parallel with the shaft B, and resting at one end in an arm or bearing, K, projecting from the standard b' of the frame, and at the other end having a bearing in a lever or holder,

h, pivoted to an arm, *N*, projecting from the standard *b* of the frame.

p is a gear rigid with the shaft *I*, and *t* a companion pinion made rigid with the shaft *B*, 5 by means of which the shaft *I* is positively rotated when said shaft *B* turns.

a is another gear made rigid with the shaft *I*, which engages the gear *k*, made to turn loose on the shaft *B*, in place of the rigid pinion *k* 10 shown in said patent, which gear *k* of my present invention engages the gear *l*, rigid upon the shaft *E*, as in my previous patent. From this construction it will be understood that the shaft *E*, with its roller *D*, is not driven directly 15 from the shaft *B*, as in my first machine, but indirectly through the medium of the shaft *I* and loose gear *k*.

In addition to the end of the shaft *I*, the holder *h* carries also an idle-gear, *c*, Fig. 4, 20 equal to and engaging the gear *a*, and so held that when said holder is turned upon its pivot *w* said gear *c* will be brought to engage the loose gear *k*, while the gear *a* will be withdrawn from said gear *k*, on account of which the direction of motion of the roller *D* will be reversed. The shaft *B*, with its roller *C*, turns 25 always in the same direction; but the direction of rotation of the roller *D* depends upon which gear, *a* or *c*, is acting upon the gear *k*.

H is an arm pivoted at *e* to the frame in a manner to move in a vertical plane, at the free end of which said arm carries a toothed cam-wheel, *G*, in position to engage a pinion, *o*, rigid with the shaft *B*. This cam-wheel is 35 paratively large in diameter and formed with a cam race or groove, *s*, upon one of its sides, and the lever or holder *h* is formed at its lower end with a part, *u*, extending into said cam-race. The cam-race *s* is given such shape as 40 to cause said lever to rock in a way to cause the gears *a* and *c* to alternately engage and turn the gear *k*, as stated, the cam-race being further proportioned so as to cause said gears to turn the gear *k* and the roller *D* in contrary 45 directions during equal periods of time.

The treadle-shaft *r* is provided with a sleeve, *v*, provided with a treadle, *L*, and an arm, *a'*, from which arm a rod, *c'*, reaches upward to the arm *H*, as shown in Figs. 1 and 8. By 50 this means the cam-wheel *G* may be raised or lowered to engage or clear the pinion *o*, as the case may be. When the cam-wheel is rotated and controls the action of the lever *h*, the gears *a* and *c* are alternately acting upon 55 the gear *k*, causing the direction of rotation of the roller *D* to be alternated, as stated; but when said cam-wheel is allowed to drop away from the gear *o* and stops rotating, the roller *D* turns in only one direction. Upon the side opposite the cam-race the wheel *G* is formed with a concentric circular projection, *h'*, which as 60 said wheel rotates rolls upon a rest or support, *e'*, secured rigidly to the frame, said rest being provided with an anti-friction roller, *i'*, which may be of some yielding material, as 65 leather or india-rubber, to render its action upon the gear less harsh. The part *h'* is formed

with a peripheral notch, *o'*, which, when it arrives at the roller *i'*, allows the wheel to drop away from the gear *o* and cease rotating. Be- 70

sides, said notch and rest *e'* serve to hold the wheel from being turned one way or the other from the jarring of the machine or other un- 75 designed causes. While the unbroken portion of the periphery of the part *h'* is passing the roller, the cam-wheel is held against the wheel *o*, and does not fall away therefrom necessarily as soon as the treadle *L* is released by the foot of the operator. When said treadle 80 is pressed, while the cam-wheel is at rest, the latter is raised off the rest *e'*, against the gear *o*, and commences to turn, the part *h'* riding upon the roll *i'*, as stated, and the cam-wheel then continues to rotate regard- 85 less of the treadle until it has made one complete revolution, bringing the notch *o'* again back to the rest. The cam-race *s* and notch *o'* are relatively so formed upon the gear *G* that 90 when said gear is stopped the part *u* of the lever *h* will be about at the middle of the concentric part or dwell of the cam having the longer radius. This, however, is not essential to the 95 successful operation of the machine, but convenient. The treadle-rod *c'* passes through a lateral projection, *l'*, of the frame, above and beneath which projection is an adjustable col- 100 lar, *l*, secured to the rod, which serve to form stops for the vertical motion of said rod, the lower collar acting to prevent the unduly crowding together of the cam-wheel and gear *o* from an excessive weight upon the treadle *L*, while the upper collar acts with the rest *e'* to support the weight of the cam-wheel, arm *H*, treadle-rod, &c. From the form and proportions of the cam-race the roller *D* is caused 105 to turn through a certain distance in one direction and back through the same distance while the cam-wheel is making one complete revolution; or, in other words, when the cam-wheel is raised by the treadle and then left to 110 itself the shirt-front will be carried past the polishing-roller twice before said cam-wheel stops, the polishing-roller stopping at the point upon the bosom at which it started. The treadle-rod *c'* is connected with the arm *H* by 115 passing upward through a lateral projection, *n'*, of said arm, said rod being threaded with one or more screw-nuts, *p'*, thereon for adjusting the length of said rod. The shaft *I* at its 120 ends rests primarily in cylindrical pieces or sleeves *r'*, held within respective parts, *K* and *h*, upon the points of opposing pivot-screws *s'*, there being spaces *t'* between the outside of said sleeves and said parts *K* and *h*, respectively, to admit of the lateral motion of the 125 shaft given it by said reciprocating arm *h*.

What I claim as my invention is—

1. In combination with the driving-shaft of an ironing-machine provided with a polishing-roller, a tight gear, *t*, and a loose gear, *k*, 130 a second rotatory shaft provided with a cov- 130 ered roller and a tight gear, the latter co-operating with said loose gear *k*, a third rotatory shaft, *I*, provided with a tight gear, held to

co-operate with said tight gear t of the driving-shaft, and a second tight gear, a , held to co-operate with said loose gear k , and a reciprocating holder for one end of said shaft I, 5 provided with an idle-gear, e , to turn said gear k alternately with said gear a , with means, substantially as shown and described, to reciprocate said holder.

2. In an ironing-machine, a shaft, B, provided with fixed gears t and o , and loose gear k , in combination with a shaft, I, provided with gears p and a , a reciprocating holder for said shaft I, a gear, e , held by said holder, a cam-wheel to operate said holder, and a shaft, 15 E, with gear l , with means, substantially as shown, to turn said shaft B, as specified.

3. In combination, in an ironing-machine, a cam-wheel with notched disk or part h' , rest e' , holder for said cam-wheel, treadle-gearing,

substantially as shown, to operate said holder, 20 a rotatory shaft with gear to turn said cam-wheel, reciprocating part h , provided with gear e , operated by said cam-wheel, shaft I, with gear a , and gears t and p , connecting said shafts.

25 4. In an ironing-machine, a shaft provided with a gear, in combination with a wheel held upon a movable arm to co-operate with said gear, said wheel being provided with a notched circular part, a rest upon which said notched part bears, a treadle-rod provided with stops joined to said movable arm, and a treadle, substantially as shown and described.

ARTHUR T. HAGEN.
